UNITED STATES PATENT OFFICE.

JAMES L. ECK, OF KUTZTOWN, PENNSYLVANIA.

SEWING-MACHINE.

SPECIFICATION forming part of Letters Patent No. 256,828, dated April 25, 1882.

Application filed May 28, 1881. (No model.)

To all whom it may concern:

Be it known that I, JAMES L. ECK, a citizen of the United States, residing at Kutztown, in the county of Berks and State of Pennsylvania, have invented certain new and useful Improvements in Sewing-Machines, of which the following is a specification.

This invention relates to that class of sewing-machines which are provided with a rotary shuttle-carrier and shuttle, and has for its object to improve the mechanism for actuating the needle-arm; also, to improve the construction of the shuttle-race and the shuttle-carrier. These objects I attain by means of the devices hereinafter described, and illustrated in the drawings, in which—

Figure 1 is a side elevation of a portion of a sewing-machine, and illustrates the devices for actuating the needle-arm. Fig. 2 is an end view of the same with the driving-wheel removed. Fig. 3 is a plan view of the under side of the bed-plate. Fig. 4 shows a front view of the shuttle-race, shuttle, and carrier, and also shows a portion of the needle-bar and presser-foot. Fig. 5 is a top view of the shuttle-race. Fig. 6 is a section through the same. Fig. 7 is a perspective view of the shuttle-carrier. Fig. 8 is a section of the same, taken on line y y, Fig. 7. Fig. 9 is a side view, and Fig. 10 an end view, of the shuttle.

Referring by letters to the several figures of the annexed sheets of drawings, in which I have principally shown only so much of a sewing-machine as will be necessary to illustrate the invention, A indicates the bed-plate, upon which is secured an ordinary goose-neck, B, in any suitable or convenient manner. The single rotary driving-shaft C, employed for actuating both the shuttle-carrier and the needle-movement, has bearings C' C' formed upon the under side of the bed-plate at or near its ends, whereby there will be but little friction, and the construction of such parts of the machine greatly simplified. The mechanism for transmitting motion from the said driving-shaft to the vibratory needle-arm E, which is supported upon the goose-neck, is constructed and adapted for operation as follows: The driving-shaft C is provided with an eccentric, C², upon which is loosely mounted the ring E'. An upwardly-extending arm, e, of said ring is connected with a vibratory elbow-lever, F, that is fulcrumed at

one of the ends to the standard or vertical portion of the goose-neck, the pivotal point of connection between the arm of the ring and the lever being at or about the center or angle formed by the two arms of the latter. To the upper end of this elbow-lever is pivoted a short link, G, that is connected at its upper end to the needle-arm, preferably by means of a ball-and-socket connection. The operation and advantages of this mechanism will be understood from the following: Supposing the needle and needle-bar (which will be actuated by the needle-arm) to be raised from the cloth-plate and the parts just described to be so timed that the arm of the ring upon the eccentric will at such juncture be at or about the extent of its downward throw, then, as the eccentric continues to revolve, the connections between the eccentric and the needle-arm will operate so as to vibrate the latter and cause the needle-bar to descend. When the needle reaches the lowest point in its movement the relative position of the ring and arm, the elbow-lever, and the link or connecting-rod that connects the latter with the needle-arm will be in the position, or nearly so, shown in Fig. 2. Now, as the arm of the ring upon the eccentric is brought to a vertical position, or to the fullest extent of its upward throw, it is evident that the elbow-lever will be moved upon its fulcrum to a further extent, and that by means of the pivotal connection of its upper arm with the connecting-rod the latter will be swung to one side without further elevating the rear portion of the needle-arm to any extent, so as to cause further depression of the needle, and that as the elbow-lever is vibrated back again by the arm on the ring in the downward throw of the said arm the tension of the connecting-rod will be so slight on the needle-arm as not to actuate the same so as to raise the needle to any extent until the arm of the ring, the elbow-lever, and the connecting-rod are in line, as about shown in Fig. 2.

The above-described cessation or pause of the vibration of the needle-arm gives the shuttle-carrier that is upon the forward end of the driving-shaft C time to pass through the loop formed by the thread of the needle. It also permits a positive and effective movement of the shuttle-carrier, and will be found simple, substantial, easy, and noiseless. Also, by

means of this movement I am enabled to use a larger shuttle and bobbin than in the sewing-machines now in use.

H indicates the shuttle-race, the inner face 5 of its nearly-annular track being beveled inwardly, as indicated at h, Fig. 6, in order to form a receptacle for maintaining the shuttle within the race. The rotary shuttle-carrier I is fastened to a semicircular plate, i, which is 10 secured to the end of the shaft C, as illustrated by dotted lines in Fig. 4. The connection between this plate and the shuttle-carrier is effected by means of screws K, passing through slots K' in the shuttle-carrier, whereby the latter can be adjusted and tightened up a little 15 toward the shuttle in case of too much play of the shuttle during operation.

The shuttle-carrier is recessed at its upper portion, as at L, and beveled with an inward 20 slant along the sides and bottom of said recess, as indicated at l, Figs. 7 and 8, the said recess constituting a seat for the shuttle M, and its bevel-walls serving to prevent the shuttle from falling out.

25 The shuttle-race is cut away at its upper portion so as to form an enlargement, N, in the race. This enlargement serves two purposes. First, it affords space for the thread to form a loop for the shuttle to pass through, as usual; 30 and, secondly, it admits of the removal of the shuttle without detaching its carrier. The face of the shuttle-carrier is convexed or turned inwardly at one corner, i², of its recessed portion, and abruptly beveled at such point from 35 its outer to its inner face. This beveled portion, being at the rear enlarged edge of the shuttle when the latter is seated in the carrier, prevents the carrier from catching the threads during the operation of the machine. The 40 shuttle-carrier is also formed with a bevel, i³, from about a line along its screw holes or slots down to its bottom edge, this conformation being best shown in Fig. 8, and is designed for the purpose of allowing the thread to pass easily 45 over during the operation of sewing, it being understood that the stitches are formed upon the same plan as on other rotary-shuttle machines.

It will be observed by referring to Fig. 7 50 that the bottom of the recessed portion of the

shuttle-carrier increases in width from one end to the other, the projection i⁴ at the thickest part of the shuttle-carrier having a beveled inner wall, i⁵, that is at an oblique angle to the inner face of the shuttle-carrier. The forward 55 beveled end, m, of the shuttle rests against this oblique wall i⁵, the beveled projecting point i⁴, that is in front of the shuttle-point, serving to throw the thread away from the needle and to form a clear way for the shuttle to 60 pass, and also to make the stitch uniform.

The shuttle, which is formed with a slight bevel, M', fits between the two beveled end walls of the recess in the carrier, and will, by means of the conformation of the devices described, be at all times maintained in proper place.

Having thus described my invention, what I claim, and desire to secure by Letters Patent, is—

1. The combination, in a sewing machine, of the driving - shaft, the eccentric thereon, the arm e, the right-angle elbow-lever F, pivoted by one arm to the goose-neck B, and to which the arm e is pivoted, and the link G, connected 75 to the needle-arm E and pivoted to the other arm of the elbow-lever, the relation of the parts being such that the distance from the needle-arm to its pivot on the elbow-lever and the distance from that pivot to the pivot of the 80 elbow-lever on the goose-neck are equal, whereby the needle - arm and its bar are held substantially at rest for a moment when they are in their lowest positions, substantially as and for the purpose set forth.

2. The combination, in a sewing-machine, of the shuttle - race H, cut away to form the enlargement N, in order to provide space for the loop, and also to admit of the removal of the shuttle without detaching its carrier, with the 90 rotary shuttle-carrier I, formed with a beveled recess, and the shuttle M, adapted to fit into and be retained in the said beveled recess of the shuttle-carrier, substantially as described.

In testimony whereof I affix my signature 95 in presence of two witnesses.

JAMES L. ECK.
